F. M. SIMPSON,
RAIL PLATE,
APPLICATION FILED MAY 3, 1913.

Patented June 1, 1915.

UNITED STATES PATENT OFFICE.

FRANK M. SIMPSON, OF ALAMEDA, CALIFORNIA.

RAIL-PLATE.

1,141,428.

Specification of Letters Patent. Patented June 1, 1915.

Application filed May 3, 1913. Serial No. 765,376.

To all whom it may concern:

Be it known that I, FRANK M. SIMPSON, a citizen of the United States, residing at Alameda, in the county of Alameda and State of California, have invented certain new and useful Improvements in Rail-Plates; and I do hereby declare the following to be a full, clear, and exact description of the invention, such as will enable others skilled in the art to which it appertains to make and use the same.

This invention relates to new and useful improvements in rail plates, and has for its object to provide a plate which will co-operate with the spikes whereby said spikes will be held substantially immovable.

Another object of my invention is to provide a spike having ratchets adapted to engage the rail plate when the device is in operation.

A still further object of my invention is to provide a device which may be used on any type of rail plate by making a slight variation in the spike apertures.

With the above and other objects in view, I will now proceed to describe my invention in the following specification and accompanying drawings, in which,

Figure 1 is a transverse sectional view of my improved rail plate showing the same as it would appear when in place on a tie; Fig. 2 is a longitudinal sectional view of my improved rail plate similar to Fig. 1; and Fig. 3 is a fragmental view of my improved rail plate showing the spike aperture as it would appear in plan.

Referring to the drawings by characters of reference, 5 indicates generally a rail of the usual construction, comprising a head 6, a web 7 and the flanges 8. This rail 5 is mounted in the usual manner on a tie 9 and is adapted to seat on a rail or wear plate.

The rail plate mentioned above comprises the main body portion 10, upon which the rail is adapted to rest, and the laterally extending portions which extend beyond the flange of the rail and are adapted to overlie a portion of the tie, and thereby distribute the wear over a greater area. This plate is provided intermediate the body portion 10 and the laterally extending portions 11 with apertures 12 adapted to receive spikes. I provide longitudinal slits 13 on each side of the apertures, these slits being adapted to separate the tongues 14 from the body por-

tion and the laterally extending portions, as clearly illustrated in Fig. 3.

In connection with my improved rail plate, I use the spike, as illustrated at 15, provided intermediate its length with the lateral enlarged portions 16, having transverse grooves extending thereacross, as illustrated at 17, which form teeth, as clearly illustrated in Fig. 2, these teeth being adapted to engage within the tie 9 to prevent upward movement of the spike therein and also adapted to engage the tongues 14 on the rail plate, whereby the spike is held firmly against upward movement relative to the plate 10. One end of the spike is provided with a point 18, which is adapted to be driven into the wood of the tie, and the opposite end is provided with a head 19, which overlies a portion of the rail flange, as clearly illustrated in Fig. 1.

In use the ties are laid in the usual manner and the rail plate laid in the desired position thereon. The rail is then placed in position on the rail plate and the spikes 15 driven through the apertures 12.

As clearly illustrated in Fig. 2, the inner free ends of the tongues 14 are depressed upon the insertion of the spike and compress the fibers in the portions of the wood tie 9 underlying said tongues. When the spike 15 is driven to its proper position to engage the head 19 thereof with the rail base 8, the free extremities of the tongues 14 are engaged behind the uppermost pair of teeth 17, and thus reliably lock the spike against upward movement relative to the plate 10. The teeth 17 below the tongues 14 are embedded in the compressed portions of the tie underlying said tongues and thus effectively prevent upward movement of the spike relative to the tie 9.

While in the foregoing I have shown and described the preferred embodiment of my invention, I wish it to be understood that I may change the specific arrangements of parts without in any way departing from the spirit and scope of my invention.

Having thus fully described my invention what I claim is:

In combination, a wood tie, a rail plate positioned upon said tie having apertures and slits extending outwardly from said apertures forming tongues disposed transversely of said tie, a rail positioned on said plate between said apertures, spikes includ-

ing shanks positioned through said apertures and in said tie, and heads engaged against the base of said rail, the shanks of said spikes having lateral enlargements adjacent the heads to depress said tongues and compress the fibers in the portions of the wood tie underlying said tongues, and teeth formed on said enlargements embedded in the compressed portions of said tie and engaged with said tongues to prevent upward movement of said spikes.

5 In testimony whereof I affix my signature in presence of two witnesses,

FRANK M. SIMPSON.
